UNITED STATES PATENT OFFICE.

MAC N. MCKINNEY, OF JACKSON, MISSISSIPPI.

CHURN.

SPECIFICATION forming part of Letters Patent No. 296,202, dated April 1, 1884.

Application filed February 18, 1882. Renewed February 5, 1884. (No model.)

To all whom it may concern:

Be it known that I, MAC N. MCKINNEY, of Jackson, in the county of Hinds and State of Mississippi, have invented certain new and useful Improvements in Churns; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my improved churn power and dasher. Fig. 2 is a perspective view of a portion of the top part of the frame, one of its side pieces having been removed to show the double crank and its belts. Fig. 3 is a sectional view through the double crank and the buckled end of one of the belts attached to it. Fig. 4 is a transverse vertical section through the pulley-box, pulley, and coupling-sleeve; and Fig. 5 is a perspective view of the lower part of the dasher-staff and dasher.

Similar letters of reference indicate corresponding parts in all the figures.

My invention has relation to churning with rotary reciprocating dashers; and it consists in the construction of the dasher, as hereinafter more fully described and claimed.

A designates the platform or bed-piece upon which the churn-body (indicated by dotted lines in Fig. 1) is placed. At one end of the platform is a post or standard, B, suitably braced, to the top of which is secured a frame composed of two parallel side pieces, C C, connected at their outer end by parallel cross-pieces D D, said frame, it will be seen, forming an arm of suitable length extending from the top of post B parallel to the platform or bed-piece A. In each of the side pieces C is a box or bearing, D', for the ends of the double crank E E'. These boxes slide in slotted ways e e in the sides C, in which they may be properly adjusted by binding-screws d d to regulate their distance from the outer end of the arm or frame. The sliding boxes having been properly adjusted in their ways to take up slack of the belts, they are fixed in their places by screwing up the binding-screws d d until their heads press or bind against the sides of the ways e e across the slot formed by

said ways, as shown in Fig. 1 of the drawings—that is to say, the ways e being slightly dovetailed in cross-section, and the sliding boxes D' being similarly dovetailed, the tightening of the screws d d, so as to bring their heads transversely across the ways, will operate to wedge the boxes firmly in their ways. The double crank E E' has a crank and handle, E², for rotating it.

F and F' are belts or bands, of leather or other suitable material, which are buckled at f and f', respectively, around metallic sleeves or collars e e', placed upon the cranks to prevent wearing of the belts. By shifting the position of the buckles f and f' the bands may be tightened to take up slack when required, which may also be effected by moving the boxes D' in their slotted ways e.

The dasher-staff (shown at G) is inserted into a sleeve or thimble, H, at the lower end of the pulley-shaft I, and held therein removably by the set-screw i.

K is the pulley or drum, which is journaled between the parallel end pieces, D D, as shown in Fig. 4, and has secured to it the ends of the belts F and F', which are wound around it in opposite directions. By turning crank E² a rotary reciprocating motion is imparted to the pulley K and dasher-staff G by means of the belts F and F', and this without the jerky motion which results from the employment of the usual crank-and-pitman mechanism. The lower part of the dasher-staff G is cut off tapering, as shown at g, and has a cross-head, h, at its lower end, from which two arms, k k, project upward on opposite sides of the staff, parallel to each other. These arms increase in width toward the top, 90 where they are cut off slantingly, as shown at k' and k', (see Fig. 5,) the slants or inclines being in opposite directions. It will also be seen that the cross-head h is beveled on both sides of the central tapering staff, G, as shown at the rounded parts h' and h', forming a sharp ridge on each side. By this construction of the dasher and its staff a downward draft will be created in the center of the churn and an upward draft or current along its sides, caused by the beveled side wings or arms, k k' and k k', thus causing a thorough agitation of the cream and commingling of the butter globules. This shape of the dasher also admits of the

ready removal of the butter when made, without the necessity of removing the dasher from the churn.

I am aware that it is not new to operate a churn - dasher by means of belts or bands wound around a pulley at the head of the staff or around the staff itself, nor do I lay any claim to this construction and arrangement, broadly; but,

10 Having thus described my improvement, I claim and desire to secure by Letters Patent of the United States—

The dasher composed of the staff G, cut away or tapered on opposite sides, *g*, at its

lower end, cross-head *h*, of even width with 15 the lower end of staff, and parallel solid arms *k* *k*', of increasing width from the cross-head *h* toward the top, and cut off to form inclines *k*' *k*', slanting in opposite directions, the whole made in one piece, as and for the purpose 20 herein shown and described.

In testimony that I claim the foregoing as my own I have hereunto affixed my signature in presence of two witnesses.

MAC N. MCKINNEY.
